UNITED STATES PATENT OFFICE.

ALVIN G. SHERMAN, OF DETROIT, MICHIGAN, ASSIGNOR TO THE DETROIT VAPOR STOVE COMPANY, OF DETROIT, MICHIGAN, A CORPORATION OF MICHIGAN.

HEAVY-HYDROCARBON BURNER.

1,149,300.

Specification of Letters Patent. Patented Aug. 10, 1915.

Application filed October 19, 1914. Serial No. 867,282.

To all whom it may concern:

Be it known that I, ALVIN G. SHERMAN, a citizen of the United States, residing at Detroit, county of Wayne, State of Michigan, have invented a certain new and useful Improvement in Heavy-Hydrocarbon Burners, and declare the following to be a full, clear, and exact description of the same, such as will enable others skilled in the art 10 to which it pertains to make and use the same, reference being had to the accompanying drawings, which form a part of this specification.

This invention relates to heavy hydrocarbon burners, that is, burners which burn kerosene. Kerosene cannot be ignited in pool form but must be vaporized when in pool form in order to be ignited. The burner to which my invention is applied 15 is a burner which uses the kerosene without a wick. It is therefore, necessary to slightly vaporize the kerosene before it can be ignited. For this purpose it has been customary to use gasolene as a 20 primer. By priming is meant the vaporizing of the kerosene by heating so that it 25 will take fire.

Figure 1, is a plan view of the burner. Fig. 2, is a cross section.

30 *a, a* are annular V-shaped troughs 35 mounted by a plurality of air-governing rings *b, b* which form combustion chambers to which the air is admitted. This form of burner has already been patented so it needs 40 no further description. The outer annular trough is provided with two obliquely-disposed nipples which are part of the casting forming the trough. The nipple *c* receives the heavy hydrocarbon fluid, while the nipple *d* receives the lighter hydrocarbon fluid.

I find that it is very essential that the nipple *d* have its passage correctly positioned with respect to the trough *a*. It must be obliquely disposed so that the priming 45 fluid may be discharged into the trough without the possibility of creeping back into the nipple and through the joint of the conduit *e* with the nipple, which is a slip joint. It is also desirable to have the passage in 50 the nipple *d* discharge in the trough above

the bottom thereof, so that the fluid will not creep back up the passage and out of the joint and also so that the heavier hydrocarbon will not creep up the passageway and out the joint. Oil has a pronounced 55 tendency to creep and it is essential that a guard be provided to prevent this creeping so that the oil will not reach the exterior where it will make a bad odor and greasy spots.

The main supply of hydrocarbon, that is, the heavier hydrocarbon, flows through the pipe *f* to the nipple *c*. The valve *g* controls this pipe. The pipe *f* is screw threaded into the nipple.

The conduit *e* is attached to the funnel *h*. This funnel and its conduit is of sufficient capacity to hold a measured quantity of gasolene that is sufficient to prime the burner. The funnel is located under the 70 stove bed *i*, except as to a hood *j* which protrudes at the front of the bed and which is securable thereto by the screws *k*. The hood is provided with an opening *l* in which the spout of the primer can be inserted. This 75 hood arrangement conceals the priming funnel and also presents a neat appearance for the front of the stove. When the screws *k* are removed, the funnel may be easily taken out by merely drawing the conduit out of 80 the nipple *d*, as only a slip joint is used.

What I claim is:

1. In a stove having a burner for consuming heavy hydrocarbons, the combination of a stove bed, a burner trough, a fuel 85 supply pipe leading into the burner trough, a nipple on the burner trough, a conduit having a slip joint with said nipple and provided with an upper funnel portion mainly located under the bed of the stove 90 but provided with a protruding hood portion secured to the bed of the stove and having an opening through which fuel may be introduced.

2. In a stove having a burner for consuming heavy hydrocarbons, an annular burner trough in the form of a casting provided also with an integral nipple cast to project outwardly and upwardly from the bottom of the trough, the opening through the nip- 100

ple discharging into the trough above the bottom, a conduit adapted to fit into the nipple by a slip joint, and a funnel on the upper end of the conduit, the said conduit and funnel being detachably supported on the stove, substantially as described.

Copies of this patent may be obtained for five cents each, by addressing the "Commissioner of Patents, Washington, D. C."

In testimony whereof, I sign this specification in the presence of two witnesses.

ALVIN G. SHERMAN.
